Primary Examiner — Andrew Kerr*Assistant Examiner* — Chariton Alexakis(74) *Attorney, Agent, or Firm* — Leydig, Voit & Mayer, Ltd.(57) **CLAIM**

The ornamental design for a packaging sleeve for foodstuffs, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a packaging sleeve for foodstuffs showing our new design, and,

FIG. 2 is a perspective view thereof, in a condition of use. The de-emphasized or half-toned areas in FIG. 2 depict portions of the packaging sleeve for foodstuffs that form no part of the claimed design.

1 Claim, 2 Drawing Sheets
(2 of 2 Drawing Sheet(s) Filed in Color)
